Primary Examiner — April Rivas*Assistant Examiner* — Jillian Mazzola(74) Attorney, Agent, or Firm — Kirk A. Buhler; Buhler & Associates Patenting(57) CLAIM

The ornamental design for a pocket tie, as shown and described.

DESCRIPTION

FIG. 1 is a front elevation view of a pocket tie, showing the new design;

FIG. 2 is a left-side elevation view thereof;

FIG. 3 is a right-side elevation view thereof;

FIG. 4 is a rear elevation view thereof;

FIG. 5 is a top plan view thereof; and,

FIG. 6 is a bottom view thereof.

The broken lines in FIGS. 1 and 4 depict portions of the pocket tie that form no part of the claimed design.

1 Claim, 2 Drawing Sheets(56)
